METHOD AND APPARATUS FOR OPERATING
OIL WELLS

John A. Zublin, Bel Air, Calif.

Application May 7, 1934, Serial No. 724,381

31 Claims. (Cl. 166—21)

This invention relates generally to the production of petroleum, and more particularly to the production of petroleum from flowing wells in such a manner as to retain and conserve as much as possible the gas which supplies the energy for lifting the oil to the surface.

This application is a continuation in part of my copending applications Serial No. 627,317, filed August 3, 1932, on "Method of and apparatus for removing oil from the ground", and Serial No. 663,018, filed March 27, 1933, on "Method of removing oil from an oil well". Briefly, this invention has been developed for the purpose of releasing from the oil, while still under well pressure and as yet not delivered to the ground surface, a much larger portion of the gas content than can possibly be released by pressure drop alone, or by devices now known. Subsequently a major portion of the released

gas is separated from the oil and discharged from the eduction tube into the well space exterior to the tube, from whence it passes back into the depleted oil sands for storage and maintenance of formation pressure until such time as it can be more efficiently used.

As is well known, oil and gas usually occur together, and are under a tremendous pressure while in the oil bearing formation. Although conditions vary widely from one oil field to another, some gas generally is found in the free gaseous condition, while a large amount is dissolved in the oil; and also some gas is generally believed to be occluded by the oil. Also, under the high formation pressure, some constituents will be found existing as liquids while at atmospheric pressure these same constituents will be gaseous; and it will be readily understood that such volatile fractions when in the oil sand in liquid form are mixed or dissolved in the heavier non-volatile fractions, that constitute what may be termed fixed oil. The term "gas" as herein used refers to all substances that will become gaseous when the oil is raised to the ground surface, and includes not only the gas which exists free as such in the oil sand but also all dissolved and occluded gas and volatile fractions of the oil which become gaseous under relatively lower pressures that may exist in the well or under atmospheric pressure. Within the oil sand the fixed oil and gas are so thoroughly intermingled as to form a substantially homogeneous fluid in which the liquid and gaseous phases are indistinguishable. The oil in its original condition including gas, whether dissolved or occluded, or as a volatile constituent, is herein termed

"native" or "gas-charged" oil in contrast with the fixed oil remaining after delivery to the ground surface and loss of the gas content.

The formation pressure forces the native oil into the well bore, and, together with the energy released by the expanding gas under reduced pressures, lifts the oil to the ground surface. The energy available to lift the oil may be considered that produced by the expansion of the gas during its removal from the well. The gas, being much less viscous than oil, passes through the formation more easily and reaches the well more rapidly, having a tendency to escape from or "side-track" the oil, leaving the latter behind in the sands. At first there is a large excess of energy available in the gas present and the oil is easily lifted to the surface; but sooner or later the quantity of gas available decreases and there is no longer sufficient available energy to lift the oil. When the well no longer flows, it is necessary to install pumps to extract the oil, obviously increasing the cost of production, and this is important when it is realized that the oil remaining in the sands when pumping becomes necessary may be as much as 90% of the original quantity of oil.

Experience has shown that when a well is allowed to flow freely, the gas content is relatively quickly exhausted, leaving behind a large part of the oil which must be pumped out. And furthermore the escape of gas from the sand removes the pressure forcing the oil into the well so that a large part of the total oil in the formation, perhaps as much as 80%, cannot be recovered at all.

When a well is operated in such manner as to limit the rate of flow of oil and gas to some point below free flow, the result is to increase the life of the well and increase the proportion of oil recovered as well as decrease the unit production cost.

The quantity of gas usually amounts to several thousand cubic feet for each barrel of oil; and since irregular productions of large amounts of gas cannot be used commercially but are largely wasted, state regulations customarily place a limit on the maximum gas-oil ratio allowable where the gas is not used. This ratio is the volume of gas produced per unit volume of oil. When the well cannot be regulated so as to flow at less than the maximum allowable gas ratio, the well is shut down and it means that an investment of many thousands of dollars becomes non-productive.

Heretofore this regulation of a flowing well,

i. e. a well emitting oil under its own gas pressure, has been done by means of a casing head or some plug in the well permitting the retention of gas pressure (commonly known as back pressure) on the well liquid, and by a valve at the top end of the oil eduction tube regulating the flow of oil and, consequently, the pressure in the well.

Retaining a well under pressure by limiting its rate of flow lessens the gas wastage and tends, with narrow limits, to decrease the gas-oil ratio, but is still not sufficient in most instances to reduce the gas-oil ratio to less than the allowable maximum. The reduction of this ratio cannot be accomplished by mere restriction of flow, since this operates to increase the casing pressure in the well, creating a back pressure on the sands that reduces the seepage of oil and, if great enough, eventually increases the gas-oil ratio by stopping oil flow. Furthermore, at the top of the well the gas has expanded to a relatively large volume while the oil has retained its original volume and is relatively much smaller than the gas, so that the bulk of the fluid volume regulated by restriction means at the well top, is gas and the result is to reduce oil flow at a greater rate than gas flow is reduced. For these reasons, attempts to materially reduce the gas-oil ratio by simple flow control at the top of the well fails to attain the desired end.

After natural flow has ceased, flow may again be had artificially by repressuring, which involves the pumping of gas under high pressure into a well to force oil through the sand to adjoining wells. This method is expensive, since energy is put back into the gas by compressing it, and the method, being used only after natural flow has ceased, accomplishes no conservation or regulation of the potential energy in the original well fluids.

It thus becomes a general object of my invention to decrease the quantity of gas removed from a well relative to the oil removed, i. e. the gas-oil ratio, to within the legal limits, and preferably to approximately that quantity that will produce the energy required to bring the oil to the ground surface. In this manner the gas flow is relatively uniform over a longer period of time and can be used to better commercial advantage.

Another object of my invention is to use as much as possible of the potential energy in the well fluids for raising oil to the surface to the end that more of the oil may be recovered from a given well, and that the production costs will be as low as possible.

Another object of the invention is to extract from the gas charged oil a portion of the gas or energy contained in excess of that required to lift the oil to the surface of the ground, and to store this energy in the form of compressed gas for further use in delivering to the ground surface additional amounts of oil.

A further object is to store and use the extracted gas within the same well and adjoining sands wherein the gas originated without removing the gas from the well for storage or between extraction and its final use.

These objects are accomplished by releasing gas from the gas-charged oil in excess of the amount normally released by the pressure reduction occurring as the oil passes from the remote sands into the well bore. In general, this release is accomplished by violently agitating the oil. A

portion of the gas so released is collected under pressure which, because of the agitation of the oil, becomes greater than the fluid pressure in the upper portion of the producing sand of the well, so the collected gas is discharged into the well, from which it passes into the gas zone or top portion of the oil sand by virtue of the high well pressure. After return to the sand, the gas is again available to force additional oil out of the sand and up the eduction tube so that a higher percent of the total oil is recovered and the lifting power of the gas is more effectively used over a longer time.

In a device embodying my invention I provide means to violently agitate the gas-charged oil as it rises in the oil string to release the gas which is then separated from the oil and collected in a suitable chamber. Gas pressure in the chamber, when greater than the well pressure, forces gas through a suitable outlet into the well exterior to the eduction tube, which is kept at a predetermined pressure sufficient to force gas into the gas zone, by means of a casing head or other suitable pressure retention means. The oil still contains at least sufficient gas to lift it to the surface. A large amount of released gas is not separated but remains in the oil stream, so there is formed a highly gasified fluid of less density than the fixed oil.

A true understanding of my invention will be more easily had if the distinction between the steps of releasing gas and separating gas from oil is kept in mind. The native oil contains gas in one or more of these conditions: dissolved either as a vapor phase in a liquid phase or as a liquid phase (the gas which is liquefied at formation pressure) in a liquid phase; occluded by the oil; free gas mixed with the oil. The free gas is physically distinct from the oil and needs only to be separated out by a suitable method.

The dissolved and occluded gas is physically indistinguishable from the oil and the first step in its extraction is to release it from solution or occlusion so that it becomes "free" gas which first appears as small bubbles entrained in the oil because of the latter's high viscosity. The oil with gas entrained in it forms, in effect, a gas-oil mixture of which the components can be separated by several methods, the commonest being a gravity separation utilizing the difference in densities.

The term "release" is used herein to designate the formation of gas as a distinct physical phase from the gas which is dissolved or occluded in the oil, while "separation" refers to the subsequent step of separating the two different phases when they are together in a gas-oil mixture.

The distinction made is essentially that which exists between segregating the constituents of a solution and the constituents of a mixture, and the steps are distinct just as a solution is distinct from a mixture. For example, a true solution is relatively stable, but a mixture will segregate when the components are of different densities. Of course solutions and mixtures blend, and so may the steps of release and separation. Indeed the two steps may be carried on together and appear to be but one as the gas extraction is a continuous process, but nevertheless the two steps take place successively as the physical inter-relations of the oil and gas change.

How the above and other objects and advantages of my invention are attained will be best understood by reference to the following descrip-

tion, wherein are described various forms of my invention, and the annexed drawings, in which:

Fig. 1 is a diagrammatic vertical section of one form of my invention in position in a well;

Fig. 2 is a vertical median section, longitudinally contracted, of gas and oil agitating and separating means constructed in accord with my invention;

Fig. 3 is a horizontal section on line 3—3 of Fig. 2;

Fig. 4 is a horizontal section on line 4—4 of Fig. 2;

Fig. 5 is a horizontal section on line 5—5 of Fig. 2;

Fig. 6 is a perspective view of a single rotor removed from the remainder of the device;

Fig. 7 is a vertical median section, longitudinally contracted, of a variational form of my invention;

Fig. 8 is a broken horizontal section on line 8—8 of Fig. 7;

Fig. 9 is a horizontal section on line 9—9 of Fig. 7;

Fig. 10 is a horizontal section on line 10—10 of Fig. 7;

Fig. 11 is an enlarged fragmentary vertical section, partially in elevation, of the oil agitating elements of Fig. 7;

Fig. 12 is a horizontal section on line 12—12 of Fig. 11;

Fig. 13 is a fragmentary vertical median section showing a variational form of gas discharge valve;

Fig. 14 is a fragmentary vertical median section showing a variational form of agitating and separating elements;

Fig. 15 is a horizontal section on line 15—15 of Fig. 13;

Fig. 16 is a horizontal section on line 16—16 of either Fig. 7 or Fig. 13;

Fig. 17 is a horizontal section on line 17—17 of Fig. 14.

Without any further preliminary discussion of operation, I shall now proceed to a detailed description of my invention, one form of which is shown diagrammatically in Fig. 1, in place in a typical well. The well is provided with a casing 20 cemented at 21 to the hard formation 22 overlying oil sands 23. Within casing 20 there is an oil string 25 provided with a perforated bottom portion 26 extending into the oil sands and through which the oil passes to reach the oil eduction tube. The oil is delivered to the surface of the ground through eduction tube 28, located within the oil string, and provided at its upper end with regulation valve 30 or any other suitable means of controlling the rate of flow of oil through tube 28. The upper ends of casing 20 and oil string 25 are sealed by heads 32 and 33 respectively in order that a predetermined pressure may be maintained upon the well liquid, although it will be understood that any other suitable type of plug or sealing means may be used in order to retain gas pressure within the well.

There is generally indicated at 35 a shell which, as will be explained, may be considered as an enlarged end portion of eduction tube 28, and which houses the agitating and separating means illustrated in greater detail in Figs. 2 to 6. In these latter drawings, it will be seen that there is secured to the lower end of tube 28 coupling 36 and sleeve 37 provided with a hard metal lining 38 forming an orifice 39 through which the upwardly moving oil passes before entering tubing 28. To the lower end of sleeve 37 is secured valve section 40 containing ball-check valve 41 having

a valve seat 42. Valve section 40 is formed with a transverse gas passage 43 above the valve 41, and with longitudinal oil passages 44, as may be seen by reference to Fig. 3.

Supported from valve section 40, by means of couplings 46 and 47, is tubing 35 which is of relatively great vertical extent, for reasons later explained, and which forms a housing for the gas extraction elements. Secured to an internal bore within valve section 40, is tubing 50 which provides a gas collection chamber 51 closed at its upper end by valve 41, or any other suitable type of pressure actuated valve mechanism. By this arrangement, gas accumulated in chamber 51 under pressure can open valve 41 and pass through passage 43 into well space exterior to shell 35. Oil rising within shell 35 flows through annular space 48, between tubings 35 and 50, and passages 44, in valve section 40, and thence into upper portion 28 of the eduction tubing.

Means for agitating the gas-charged oil and for separating the released gas from the oil are attached to the lower end of tubing 50. The top-most element of said means is section 54 which for convenience of designation will be hereinafter referred to as a bell. This section may be provided with radial fins 55 which center the bell within shell 35. Spaced a short distance below bell 54, is a second similar bell member 56 which is supported from the upper bell by shaft 57 that has its ends screwed into hubs 58 and 59 of the upper and lower bells respectively. As illustrated in Fig. 4, hub 59 is provided with vertical passages 60 through which fluids may move upwardly. Similar passages are provided in hub 58.

In the space between the two bells there is located a centrifuging rotor 63 journaled on shaft 57 and adapted to be revolved by the fluids leaving passages 60 located immediately beneath the rotor. Although the rotor may take any suitable shape, a preferred form is illustrated in Figs. 5 and 6 in which the rotor is generally cup-shaped with upwardly extending vanes 64 formed in the sides by means of inclined slots 65.

The agitating and separating means accomplishing gas extraction is made up of a series of bells 56 connected by means of shafts 57 in the manner described, and a plurality of rotors 63 journaled one upon each of the shafts in the spaces between the successive bells, as illustrated. Any desired number of alternating rotors and bells may be used depending upon the physical characteristics of the oil in the well and the amount of gas that it is desired to extract from the oil. Thus it will be seen that gas-carrying oil entering the lowermost bell 56a of the series, rises through passages 60 and strikes vanes 64 of rotor 63 with the result that the rotor is revolved and a centrifuging motion is given to the oil. The rising oil stream first strikes lower face 67 of the bell hub, then enters passages 60, and upon leaving the passages is "chopped-up" as it strikes a rotor 63, so that sufficient agitation is created to release a portion of the gas. The fluid stream now contains constituents of varying densities so that as a result of the centrifuging the heavier liquid is thrown outwardly and the lighter gas and liquid is displaced inwardly. The heavier liquid is then carried by the upward current through passages 68 between tubing 35 and bell 56; while the lighter gas and liquid rise into the central portion of the bell 56 and through passages 60 of that bell to again be centrifuged by the rotor next above.

By repeated and alternated agitation and cen-

trifuging, an increasingly large portion of gas is released, and the gas and oil are gradually separated by virtue of their difference in densities so that as the fluids rise within shell 35 they form 5 two increasingly distinct columns, a column of oil which has been deprived of a large amount of its contained gas and is rising through passages 68 into space 48 around the gas separation chamber, and a central column of lighter fluid containing 10 mainly gas which rises through passages 60 of top bell 54 into chamber 51.

The elements so far described may be considered as constituting a complete stage of gas extraction elements, and it will be readily seen 15 that a plurality of such stages may be used if necessary to effect the desired release and separation of gas and oil. As an example, Fig. 2 illustrates a second stage provided with valve section 40a connected to the lower end of the first 20 stage by means of section 70. The lower stage is identical with the one described, and is so arranged that the gas from chamber 51 passes out into the well exterior to the eduction tube while the oil that has already given up part 25 of its gas content flows upwardly through passages 44, of section 40a, and section 70 into the lower end of the upper stage where further release and separation of oil and gas takes place.

In order to effect a preliminary separation 30 from the oil of the free gas occurring in the oil sands and the gas released from the oil by the reduced pressures within the well, it is preferable to provide a gas anchor which may be of any conventional type. The anchor illustrated in 35 Fig. 2 is attached to the lower end of the bottom extraction stage by couplings 71, 72, and 73, and comprises an upper length of perforated pipe 74 to which is connected a lower length of imperforate pipe 75 terminating in a bullnose 76, and an inner pipe 79 which extends downwardly 40 some distance below the perforated pipe 74, preferably to a point near the bullnose 76. Oil enters the eduction tubing by passing through perforations 77 of pipe 74 and then flowing downwardly 45 in the annular space between pipe 74 and tubing 79 before rising within tubing 79, as indicated by arrows 78. The free gas, being much lighter, will rise through the oil as it flows downwardly within tubing 75, and will collect outside of pipe 50 74 at the top of the gas anchor. This gas then returns to the well by passing outwardly through perforations 77. In practice, it is not necessary that all free gas be separated from the oil at this point; and indeed a considerable proportion of 55 it will be carried along by the oil and will enter the agitating and separating means. However, such gas will be returned to the well along with that gas which is released from the oil by the agitation occurring as it passes through the rotors and separating belts.

Functionally, the eduction tube as an entirety includes tube 28, shell 35, and pipe 79. The eduction tube begins at the only point of oil or gas entry, bottom 88 of pipe 79, and is not open to the well at any point except through the valve-controlled gas ports 43 which permit gas, but not oil, to leave the eduction tube.

The operation of the device is as follows, referring to Fig. 1, which illustrates conditions representative of actual conditions in a flowing well as far as can be ascertained.

Gas-charged oil flows from the sands into the well and is withdrawn through the eduction tube 28 at a rate to maintain a fluid level 80 which 75 may be definite or indefinite, as the sharp line

between fluid, foam and gas may be impossible to determine. The oil front in the sands is represented by line 85, the cone above this front being filled with gas which would flow almost entirely free of oil into the well if the well pressure were sufficiently low. The position and configuration of line 85 depends upon hydraulic gradient of oil flowing through the sands.

Gas dissolved in the oil forms a saturated solution under formation pressures, but when in the well under reduced pressure the solution becomes supersaturated or unstable. Extraction of additional gas, over and above that released by normal pressure drop, is most easily accomplished, without further reduction in the well pressure, 15 by agitation of the upwardly flowing oil.

This gas released from solution can then be separated from the oil and returned to the well outside the eduction tube, from whence it may be forced into the gas zone above oil front 85. 20 For example, assume an original oil front to be at 86; if any oil is now withdrawn so that the front recedes to 85, the pressure will drop correspondingly. However, if a volume of gas equal or nearly equal to the oil withdrawn is returned 25 to the formation, then there will be little or no pressure drop. Pressure sufficient to return gas to the depleted upper portion of the sands may be developed in a relatively thick oil sand because the pressure at the entrance 88 to the eduction 30 tube may be several hundred pounds greater than the pressure at the top of the sand. Naturally it is impossible to maintain a constant pressure in the formation, but large quantities of gas, otherwise withdrawn from the well, may be separated 35 and returned to the gas zone with the result of maintaining a higher average pressure and of greatly increasing the producing life of the well.

Before the oil enters the mouth 88 of the eduction tube, part of the gas will be separated out as 40 a result of a pressure drop and gravity separation; and the oil, as it passes through gas anchor 74, will have additional gas separated out.

The physical state of the oil entering the eduction tube will vary. It may be a liquid with the 45 gas in solution; or with high pressure and high gas production it may be carried by the gas in the form of a fog or a foam. Whatever the form of the gas-oil mixture, it is forced upward by the pressure jetting through passages 60 in the 50 bell 56a and impinges against the lowermost rotor 63 (see Fig. 2). Drops of oil carried by free gas deposit on the rotor surfaces while liquid oil entraining free gas is broken up by the rotor which is revolved by the upwardly 55 moving stream of gas and oil. Successive slots in the rotor passing over openings 60 cause a pulsation in the oil stream as it jets through the lower openings 60.

Centrifugal action of the rotor throws off liquid 60 to its periphery which displaces gas inwardly, thus having a tendency to concentrate the gas centrally out of the separating bells. This process is repeated at each of the separate rotors, more and more of the gas being released by the continued agitation until there is formed a relatively highly gasified column of fluid of relatively less density rising centrally of the device through openings 60, and a second column of fluid containing a large proportion of liquid and consequently of greater density rising in the annular space 68 around the separating bells.

The central column of gaseous fluid empties into gravity separation chamber 51 where the released gas separates out and rises to the top 75

of the chamber, there thus being more or less clearly defined liquid levels 83 and 83a in the upper and lower stages. In each of these stages, gas will collect in chamber 51 until the pressure therein becomes sufficient to open valve 41 and discharge the gas through ports 43 into the well space. At the open lower end of each chamber 51 the pressure within the chamber will balance the pressure around the chamber at 48. However, the gas in the chamber will have substantially the same pressure throughout its entire length, and will consequently communicate to the under side of valve 41 a pressure substantially equal to that existing at liquid level 83 which pressure increases as the liquid level drops. Thus level 83 will move downwardly until the pressure is sufficient to open valve 41 against the pressure on top of the valve through port 43. In practice, the vertical length of chamber 51 may be from 100 to 600 or more feet, allowing a similar range in the position of level 83, so that it may drop to a point such that the pressure underneath valve 41 will exceed the pressure external to the eduction tube at port 43 and discharge gas into the well space.

Under initial or irregular flowing conditions, the external pressure at port 43 will close valve 41, but normally this valve will continually exhaust gas.

Agitation of the gas-charged oil has released such a large quantity of gas that even after separating and removing some of it for return to the oil sands, the column in the eduction tube is highly gasified and contains sufficient energy to lift it to the ground surface. Further, this release and expansion of gas supplies energy which compensates for the relatively high friction losses as the fluid passes through the device.

Any change in flow conditions influencing the rate of oil entry into the well automatically changes the operation of the device to correspond, since the rate of flow of gas-charged oil controls the rate of gas release. Changes in flow may also be produced by manual operation of flow beans in the outlet of the eduction tube as illustrated at valve 30.

The device has the particular advantage that by manual operation of flow control means at the top of the well, the flow of both oil and gas is actually changed by the device at the bottom of the eduction tube where, because of smaller volume, control is easier and more effective.

Fig. 7 illustrates a variational form of apparatus embodying my invention. The operation of this form is identical with that described, the only difference being in the structure, which includes a different form of gas discharge valve, a change in the relative positions of the gas collection chamber and eduction tube, and a change in the agitation means. As before, the agitating and separating means is carried within oil string 26 on the lower end of tube 28, and connected to the latter member by means of couplings 105 and 106, which contain a hard metal lining 107, forming orifice 108, through which the oil passes to reach tube 28. Attached to the lower end of coupling 106 is valve section 110 that is provided in its upper portion with a plurality of gas outlets closed by valve 112 adapted to slide vertically upon the upper end of valve section 110 as shown. A spring 113 bears upon valve 112 to insure proper seating of the valve and closure of outlets 111. This construction is illustrated in further detail in Fig. 8.

Attached to the bottom of valve section 110 by

coupling 115 is shell 35 which, as before, may be considered as an enlarged extension of the eduction tubing. Also carried from valve section 110 but within shell 35 is tubing 120 which communicates directly with oil passage 119 in the valve section, and forms an annular space 125 between it and shell 35, to which space gas outlets 111 open directly. At intervals throughout the length of tube 120 holes 121 are cut, and at each one of these holes there is provided a semi-cylindrical member 122 secured to the outside of tube 120. By means of members 122 there are provided a plurality of downwardly extending passages 123 which open at their upper ends to the annular space 125 and at their lower ends to holes 121, thus providing a direct communication between the interior 126 of tubing 120 and the exterior chamber 125. This construction may be seen clearly in Fig. 16.

The means for agitating the oil is carried on the lower end of tubing 120 and consists of a plurality of oppositely inclined vanes, which are preferably disposed in groups, generally indicated at 128 in Fig. 7. This construction is shown in greater detail in Fig. 11. Secured to the end of tube 120 is shaft 130, upon which the agitating elements are mounted. The top element consists of a sleeve 131 secured against rotation on shaft 130 by plugs 132 formed by welding. This sleeve is provided with a plurality of inclined vanes 133 extending radially almost to tubing 35 and adapted to deflect the upwardly moving oil stream. Just below sleeve 131, there is inset into shaft 130 a layer of bearing material 134, and at this point on the shaft there is provided a rotatable sleeve 135, having a plurality of vanes 136 similar to vanes 133, but oppositely inclined. Below rotor 135 is a series of alternating stationary sleeves 131, attached to the shaft as described, and rotating sleeves 135, so arranged that vanes 136 and 133 are oppositely inclined to abruptly change the direction of the upwardly moving oil stream as the stream strikes these successive vanes. Because of the inclination of vanes 136, each sleeve 135 will be rotated by the upwardly moving oil stream. The construction of one of the rotors with its radial vanes is further illustrated in Fig. 12.

A plurality of these alternating stationary and movable elements are grouped together on a shaft 130 to form one of the agitating units or stages indicated at 128. In order to secure the desired degree of agitation to extract the gas from the oil, there are provided a plurality of such agitating units or stages 128, separated if desired by lengths of tubing 140.

At the bottom of the lowermost stage 128 there is secured a short shaft 141, having radial fins 143, as illustrated in Fig. 9, for the purpose of centering these units within tubing 35 to the end that the units may work efficiently and not scrape against the surrounding tubing.

At the bottom of shell 35 is attached coupling 144 to which is connected a gas anchor of any conventional type, here shown as comprising the elements generally described in connection with Fig. 2, namely, an upper length of pipe 74 perforated at 77 to admit oil, a lower length of pipe 75 terminating in bull-nose 76, and an inner pipe 79 communication with bore 145 in coupling 144 to convey oil from the gas anchor into shell 35.

The operation of this form of apparatus is generally the same as that of the form illustrated in Fig. 2, except for certain differences caused by changed construction, which differences will now

be explained. Agitating stages 128 are designed primarily to effect a series of abrupt changes in the direction of oil flow, so that the oil is agitated sufficiently to release the contained gas. For this reason the vanes 133 and 136 are inclined oppositely to each other, but it is not essential that they be provided upon circular members such as sleeves 131 or 135, or that alternate sets of vanes be rotatable. Efficient agitation might be secured under certain circumstances by a series of oppositely inclined stationary vanes.

While the rotation of certain of the agitating elements has a tendency to separate the oil and the released gas because of the attendant centrifuging, the essential separation of the gas is not effected at this point since the main oil stream conveys both the released gas and the oil upwardly to chamber 125 within shell 35 and above the topmost agitating unit. This chamber is in the form of an annular space surrounding tubing 120 and serves as the gas separating and collecting chamber, for the oil and gas will rise within this chamber to maintain a liquid level at some point such as 147, and the gas collected in the chamber above the liquid level will be discharged through ports 111 into the space exterior to the eduction tube. Since shell 35 which forms the outer eduction tube wall also forms the wall for the gas collection chamber, the internal oil conveying tube 120 is provided, and is in free communication with chamber 125; hence oil will flow downwardly through passages 123 and openings 121 into tubing 120, and will be conveyed through the latter member upwardly into tubing 28 for delivery to the ground surface.

Although Fig. 7 illustrates a single extraction unit comprising one separation chamber 125, yet more than one of these units may be used if desired. In such event, the lower separation unit would be provided with a valve section 110, of which the oil passage 119 would be adapted to discharge into bore 145 of coupling 144 located at the bottom end of the unit illustrated. This construction would provide two separation chambers operating in tandem, as is the case with the form illustrated in Fig. 2.

A second variational form of my invention is illustrated in Figs. 13 and 14. As in the device last described, the gravity separation chamber surrounds tubing 120 so that the construction of the upper end of the apparatus in Fig. 13 is identical with the form illustrated in Fig. 7, except that a variational form of gas-discharge valve section is shown. This valve section 150 is provided with a plurality of gas outlets 151, each closed by an individual ball 152 seating in the upper end of the outlet, which construction is illustrated in Fig. 15. The sides of the valve section are slotted at 153 to provide intermediate vertical ribs 154 that form cages to retain the balls in the valve section. Tube 156 extends centrally of the valve section to connect the interior of tubing 120 with orifice 168 in hard metal lining 107. Valve section 150 is secured to coupling 105 by section 157.

This form of device also includes a variational agitating means, illustrated in Fig. 14 as attached to the end of shell 35 by means of a series of sections 160 attached to one another. Within sections 160 are carried a plurality of separating bells 161, generally similar to bells 56 of Fig. 2. Each bell carries a short shaft 162 upon which is journaled a rotor 163, similar to rotors 63 already described; hence a view on line 5a—5a of Fig. 14 is similar to Fig. 5. The bell receives the upwardly rising oil from below in its central cav-

ity 164 and discharges it through a plurality of passages 165 to the rotor carried above the bell. This rotor is revolved by the oil stream and mechanically separates a portion of the released gas in the manner already described, so that the heavier liquid is thrown outwardly and rises in annular space 166 around the bell next above. At the upper end of each annular space 166 there is located a plurality of passages 167 which discharge the heavier oil to the rotor mounted on that bell, but to a point near the periphery of the rotor, in distinction to passages 165 which discharge to the inner end of the rotor vanes (see Fig. 17).

The agitation to release gas and the separation of that released gas by centrifuging is substantially similar to the operation as carried on in the form described in Fig. 2, and the operation of the present form will be understood from the foregoing description without any further explanation. However, it will be noted that in Fig. 2 the outer column of heavier liquid rising through passages 68 is not discharged directly into each succeeding rotor, although the column of lighter liquid rising in passages 60 is discharged directly to successive rotors in the form of Fig. 14, both passages 165 and 167 discharge to the rotors, and by reason of the radial positioning of these passages relative to the rotors, both the light and heavy columns of liquid are subjected to repeated centrifuging, but without substantial intermingling so as to destroy the benefits of previous centrifuging actions. This separation of the streams is maintained throughout the agitating elements, and the top bell 161a discharges the central column of lighter liquid not through passages 165 but through a central sleeve 170. After leaving bell 161a, the oil and gas are discharged into top section 160 which constitutes the bottom of the gas collection and separation chamber 125.

Sleeve 170 is provided with slots 171 so that if, for any reason, tube 120 should drop it would rest upon sleeve 170 and an outlet would still be had for the oil through slots 171, whereas without such slots the oil passage might become entirely closed.

After passing into chamber 125, the released gas is separated from the oil by gravity, and the oil passes out of the chamber through passages 123 and opening 121 into tubing 120, through which the oil rises to reach eduction tube 28 for delivery to the ground surface.

Gas will accumulate in chamber 125 above liquid level 172 and will be discharged through passages 151 and slots 153 of the valve section 150 by the raising of valves 152 against the external pressure, as has already been explained.

Fig. 14 is shown as provided with a coupling section 173 attached to the bottom section 160, said coupling being adapted to receive a second valve section 150, in order to operate two of these devices in tandem, the oil from the lower device being charged into the upper one through tubing 156 of the lower valve section. However, a gas anchor may be attached at this point, in which case tubings 74 and 79 will respectively replace section 150 and tubing 156.

A comparison of Figure 2 with Figures 7 and 13 will disclose that the two forms of apparatus illustrated are generally similar excepting for a change in location of the gas separation chamber. In Fig. 2, shell 35, an enlarged portion of the eduction tube, serves as a housing for the agitating and separating means and confines the discharging oil stream, while the gas is collected

in an internal pipe 50 that forms the walls of collection chamber 51. In Figs. 7 and 13, shell 35 again encloses the agitating and separating elements, but tube 28 has been provided with an extension 120 inside shell 35, so that the gas collection chamber is formed in annular space 125 enclosed by shell 35 and surrounding pipe 120 that conveys the oil discharged. The effective length of the gas collection chamber is that space 10 between the outlet valve and the top communicating member 122. In the region of chamber 125, the eduction tube is in effect double walled.

From the two forms it will be seen that in both cases the gas collection chambers are in fluid 15 transmissive connection at their lower ends with the eduction tube, so that oil freed of its gas may pass between chamber and tube with interference. In the form first described, chamber 51 opens directly to the eduction tubing. In the two 20 later forms, communication is had between the gas chamber and the eduction tubing by means of vertically extending members 122, forming passages 123 communicating at their lower ends at openings 121 with portion 120 of the eduction 25 tube.

Comparison of the two forms will further disclose that their general method of operation is identical, except for such minor changes as result from the structural change in the oil agitating elements. In Fig. 2 the oil and gas undergo a certain amount of mechanical separation prior to the gravity separation taking place in chamber 51, while in the form of Fig. 7 this mechanical separation, although present in some degree, is 30 not pronounced, and the largest amount of separation occurs within the gas collection chamber by means of gravity separation. The relation of the parts in both figures is such that pressure relations in the gas chamber and oil discharge 35 tube will be the same as explained before and will operate to discharge gas through valve 152 in the same manner as it is discharged through valve 41.

Having disclosed various forms of my invention, it is to be understood that the foregoing 45 description and annexed drawings are to be considered as illustrative of, rather than restrictive upon, the claims appended hereto, for there will occur to those skilled in the art various changes in arrangement and construction of the various 50 parts that may be made without departing from the spirit and scope of the invention. For example, I am not to be limited to the particular illustrated combinations of pressure-actuated release valves, gas extraction units, and collection 55 chambers, but any desired combination of the various forms of the parts may be used.

I claim as my invention:

1. In apparatus for repressuring oil sands flowing gas-charged oil into a well, the combination 60 of eduction tubing adapted to conduct oil to the ground surface, means to maintain a predetermined pressure on the well liquid exterior to the tubing, agitation means to release gas from the gas-charged oil, said agitating means comprising rotors revolved by the oil stream to centrifuge the oil and separate released gas, a gas chamber communicating with the tubing, and a valve controlled outlet from the chamber to the well exterior to the tubing, the chamber being 65 adapted to receive and collect the released gas under pressure in excess of the fluid pressure in the well at said outlet and to discharge gas through said outlet.

2. In apparatus for repressuring oil sands flowing 70 gas-charged oil into a well, the combination

of eduction tubing adapted to conduct oil to the ground surface, means to maintain a predetermined pressure on the well liquid exterior to the tubing, oil agitating and centrifuging means comprising a series of rotors turned by the moving oil stream to release gas from the charged oil, a gas chamber communicating with the tubing and adapted to receive and collect released gas under pressure, and means for delivering gas from the chamber to the well exterior to the tubing.

3. In apparatus for repressuring oil sands flowing gas-charged oil into a well, the combination of eduction tubing adapted to conduct oil to the ground surface, means to maintain a predetermined pressure on the well liquid exterior to the tubing, agitation means comprising a series of oppositely inclined vanes causing turbulent oil flow to release gas from the charged oil, a gas chamber communicating with the tubing and adapted to receive and collect the released gas under pressure, and means for delivering gas from the chamber to the well exterior to the tubing.

4. The method of operating a well flowing gas-charged oil into the eduction tube thereof that includes directing such oil against a moving element to thereby disintegrate it to release gas contained therein, separating within the well at least a portion of the gas so released, discharging such gas into the well external the eduction tube, and delivering the oil to the ground surface.

5. The method of operating a well flowing gas-charged oil into the eduction tube thereof that includes agitating such oil by moving elements in the eduction tube to release gas contained therein, separating within the well at least a portion of the gas so released, discharging such gas into the well external the eduction tube, and delivering the oil to the ground surface.

6. The method of operating a well flowing gas-charged oil into the eduction tube thereof that includes agitating such oil by flowing the same against reversely directed surfaces to release gas contained therein, separating within the well at least a portion of the gas so released, discharging such gas into the well external the eduction tube, and delivering the oil to the ground surface.

7. The method of operating a well flowing gas-charged oil into the eduction tube thereof that includes directing such oil against a movable element operable by such fluid flow to agitate the oil releasing gas contained therein, separating within the well at least a portion of the gas so released, discharging such gas into the well external the eduction tube, and delivering the oil to the ground surface.

8. The method of operating a well flowing gas-charged oil into the eduction tube thereof that includes jetting such oil through an aperture against a movable member to release gas contained in such oil, separating within the well at least a portion of the gas so released, discharging such gas into the well external the eduction tube, and delivering the oil to the ground surface.

9. The method of operating a well flowing gas-charged oil into the eduction tube thereof that includes passing such oil against a member rotated by the flow of fluid thereby to agitate and centrifuge such oil, separating at least a portion of the gas therefrom, collecting the gas so separated within the well, discharging such gas into

the well external the eduction tube, and delivering the oil to the ground surface.

10. The method of operating a well flowing gas-charged oil into the eduction tube thereof that includes passing such oil successively against each of a series of rotors to break up and centrifuge such oil and thereby separating it into upward moving columns of different fluid densities, collecting fluid from one of such columns 10 and discharging it into the well external the eduction tube and delivering the fluid from the other column to the ground surface.

11. The method of operating a well flowing gas-charged oil into the eduction tube thereof that includes impinging such oil against a rotating member provided with passages therethrough whereby gas is released and separated from such oil to pass through such passages and whereby oil on the surfaces of such member is centrifugally discharged from the periphery thereof, collecting at least a portion of the gas so released within the well, discharging such gas into the well external the eduction tube, and delivering the oil from which such gas 25 has been separated to the ground surface.

12. The method of operating a well flowing gas-charged oil into the eduction tube thereof that includes creating within such eduction tube an outer column of fluid of a higher average specific gravity and an inner column of lower average specific gravity by passing gas-charged oil through a series of agitating and centrifuging elements for separating oil from gas, separating such columns of fluid between zones of 30 centrifuging action, elevating both columns in the induction tube from one centrifuging zone to a higher centrifuging zone, collecting fluid from the inner column within the well and discharging it into the well external the eduction tube, and delivering the outer column of fluid to the ground surface.

13. The method of operating a well flowing gas-charged oil into the eduction tube thereof that includes agitating and centrifuging such oil during its passage through such eduction tube by rotating elements spaced throughout a sufficient length of such eduction tube to create a column of gasified fluid of sufficiently long and of an average density sufficiently low that in a 40 zone of the eduction tube during oil flow therethrough the pressure will be greater than the external well pressure at that zone, separating within the well at least a portion of the gas from such oil and discharging such separated gas into the well in said zone of higher internal pressure.

14. In a device for controlling gas-oil ratios in a producing well, an eduction tube, agitator elements therein moved by the passage of fluid therethrough to agitate such fluid to release gaseous elements contained therein, means within the well for collecting such gaseous elements, said collecting means being provided with a port for discharging such gaseous elements into the well external the eduction tube.

15. In apparatus for removing gas-charged oil from a producing well, an eduction tube within the well and centrifuging means within the well and in the path of oil flow for separating gas from such oil, said centrifuging means including a rotor having openings therethrough inclined to the axis of rotation.

16. A device as described in claim 15 and including surfaces between said openings against

which the oil impinges and from which such oil is centrifuged.

17. In apparatus for removing gas-charged oil from a producing well, an eduction tube for conducting oil to the ground surface, and oil agitation means within the well having reversely directed surfaces against which said oil is directed, adapted to release dissolved and occluded gas from the oil and to discharge such gas and oil into the eduction tube. 10

18. In apparatus for removing gas-charged oil from a producing well, an eduction tube conducting oil to the ground surface, oil agitation means having moving elements within and near the bottom of the eduction tube, said agitation means being adapted to release dissolved and occluded gas from the oil. 15

19. In apparatus for removing gas-charged oil from a producing well, an eduction tube, a series of spaced rotors in the path of oil flow 20 therein adapted to release and separate gas from such oil, and means between said rotors for maintaining the separation previously effected. 20

20. In apparatus for removing gas-charged oil from a producing well, an eduction tube, a series of spaced rotors in the path of oil flow therein adapted to release and separate gas from such oil, and means between said rotors for maintaining the separation previously effected and 30 for directing fluid flow between said rotors.

21. In apparatus for removing gas-charged oil from a producing well, an eduction tube having means therein defining substantially separate paths of flow therethrough, said defining means 35 being intermittently interrupted to permit communication between such paths and centrifuging elements located at such interruptions adapted to receive fluid passing through such paths and to simultaneously centrifuge the same whereby 40 the gas and oil are at least partially segregated and the streams in the separate paths become of different densities.

22. A device according to claim 21 and including means for collecting within the well the fluid 45 flowing through one of such paths.

23. A device according to claim 21 in which said eduction tube is provided with a port opening into the well external thereof, one of said paths being in communication with such port for 50 discharge of fluid therefrom.

24. In apparatus for removing gas-charged oil from a producing well, an eduction tube, gas separating means therein including rotary elements in the path of oil flow adapted to break up 55 and centrifuge such oil, the sections of eduction tubing therebetween having separate passages for fluid discharged from the periphery and from the central portions of said rotors.

25. A device according to claim 24 in which 60 said rotary elements are provided with slots inclined relative to the axis of rotation of said elements.

26. A device according to claim 24 in which said rotary elements comprise substantially cylindrical elements having passages therethrough inclined to the axis of rotation. 65

27. In apparatus for removing gas-charged oil from a producing well, an eduction tube and agitating means therein, said means including 70 rotary elements having surfaces inclined to the rotational axis thereof and stationary elements having passages therein adapted to direct the oil flowing therethrough against said inclined surfaces at an angle to such surfaces. 75

28. In apparatus for removing gas-charged oil from a producing well, an eduction tube, rotary elements containing inclined passages therethrough and in the path of oil flow within said tube, and stationary elements having passages therethrough reversely inclined to the passages through the rotary elements.

29. In an apparatus for removing oil from a well having gas-charged oil therein, the combination of: an eduction tube adapted to be extended into said well; a relatively long vertical separation chamber into which gas-charged oil of said well is received, said eduction tube being connected to said separation chamber; agitation means in the form of rotors adapted to be driven by said oil whereby said gas-charged oil is agitated prior to its reception into said separation chamber; and means for delivering the volatile constituent of said gas-charged oil into said well.

30. In an apparatus for removing oil from a well having gas-charged oil therein, the combination of: an eduction tube adapted to be extended into said well; a relatively long separation chamber into which gas-charged oil of said well is

received, said eduction tube being connected to said separation chamber; centrifuging means whereby said gas-charged oil is agitated prior to its reception into said separation chamber, said centrifuging means including a rotor whereby said gas-charged oil is centrifuged for throwing the oil outward and walls providing a separate passage for said volatile constituent; and means for delivering the volatile constituent of said gas-charged oil into said well.

31. In an apparatus for removing oil from a well having gas-charged oil therein, the combination of: a centrifugal separating means adapted to be placed in said well, which includes walls forming a volatile constituent passage and an oil passage, and a rotor for centrifuging said gas-charged oil so as to deliver the volatile constituent to said volatile constituent passage; an eduction pipe whereby separated oil is delivered to the surface of the ground; and means connected to said volatile constituent passage for re-delivering said volatile constituent into said well.

JOHN A. ZUBLIN.
